COOLING OF GAS TURBINE ROTORS

Frank Denison Brownhill and Paul Heinz Walter Wolff, Rugby, England, assignors to The English Electric Company Limited, London, England, a British company

Application October 8, 1947, Serial No. 778,618
In Great Britain October 9, 1946

12 Claims. (Cl. 253—39.15)

1

The invention relates to cooling of the rotors of multi-stage gas turbines and has the object to provide a gas turbine rotor construction in which the only surfaces in contact with the hot working fluid are those of the blades proper and the circumference of a drum-shaped portion intermediate adjacent rows of rotor blades. The rotor discs that carry the blades are intended to work at considerably lower temperatures and are required to be free from thermal stresses such as would occur in a disc which is heated at the rim but remains comparatively cold at the centre.

According to the invention, in a multi-stage gas turbine the main body of the rotor and the outer portion of the rotor, which comprises the turbine blades, a series of blade platforms at the inner extremity of the blade profiles and a series of independent platforms located between the blade platforms of adjacent blade rings at the same diameter as the said blade platforms enclose between them a passage for a continuous and undiluted stream of cooling air forming an insulating wall between said main body and outer portion of the rotor, the only connection through the insulating stream of air being the lower portions of the blades which, between the said blade platforms and the serrated roots by means of which they are secured into the body of the rotor, are reduced in cross-sectional area and made of sufficient length to offer a substantial resistance to the flow of heat between the said outer hot portion of the rotor and the said main body, and the only connection between the said independent platforms and the said body of the rotor being through locating arrangements of relatively small area capable of offering considerable resistance to the flow of heat.

The invention is applicable both to axially inserted blades and to circumferential fixtures, both types having preferably serrated fixings of the so-called "fir tree" type. A reduced neck is formed between the blade root platform and the serrated fir tree stub so as to provide a narrow neck for the flow of heat and at the same time a recess through which the cooling medium can flow. The cooling medium is preferably a small percentage of air tapped off from the turbine compressor and emerges into the bladed zone of the turbine on the leading edge side of the rotor blades of each stage so as to form a comparatively cool boundary layer on the blade root before mixing with the combustion gases.

In another form of embodiment high pressure cooling air is introduced into the insulating space

5 at one of the stages at the low pressure end of the rotor only, preferably the lowest stage, and then passes along substantially the whole length of the rotor in the insulating space through passages formed between adjacent blade stubs and between the reduced area portions of the blade root, these passages being shaped and proportioned so as to ensure a high degree of heat abstraction from the blade roots and from the main body of the rotor. After passing along substantially the whole length of the rotor the cooling air is then discharged into the main working fluid on the upstream side of one of the early stages of rotor blades, preferably the first stage.

10 15 This embodiment permits the economical use of larger total quantities of cooling air since the cooling air is returned to do useful work in the turbine at a pressure equal to that of the main working fluid after passing through the first stage nozzles. This together with the fact that the whole of the cooling air passes through each row of blade roots permits the use of comparatively large passages between them and thus minimizes the danger of the passages becoming 20 25 choked by foreign matter and at the same time promotes more efficient cooling due to the increased surface area.

20 25 A further advantage of this embodiment is that heat abstracted by the cooling air from the low pressure portions of the turbine is returned to the cycle at a higher pressure and therefore with higher availability for conversion into work thus making the cycle to some extent regenerative and increasing its efficiency.

30 35 In order to be better understood and readily carried into effect, the invention is illustrated by way of example in the accompanying drawings of which:

35 40 Fig. 1 is a side elevation in section of part of three consecutive rotor discs having axially inserted blades with series flow cooling means arranged between adjacent discs,

40 45 Fig. 2 is part of a front elevation of a rotor disc and intermediate pieces corresponding to Fig. 1,

45 Fig. 3 is a side elevation in section of part of two consecutive rotor discs having axially inserted blades with parallel flow cooling means arranged between adjacent discs of a built-up rotor,

50 Fig. 3a is a broken-off perspective view of two consecutive rotor discs shown in Fig. 3, developed into a straight line.

Figs. 3b, 3c, 3d, and 3e are details of the construction shown in Fig. 3,

Fig. 3f is part of a front elevation like Fig. 2, 55 of the embodiment of Figs. 3, 3a—e,

Fig. 4 is a side elevation in section of part of three consecutive rotors of the circumferential fixture type,

Fig. 4a is a broken-off perspective view of the construction shown in Fig. 4, developed into a straight line;

Fig. 4b is a line diagram of the flow of the cooling medium in the said construction,

Fig. 4c is part of a front elevation like Fig. 2 of the embodiment of Figs. 4 to 4a-b;

Fig. 5 is a side elevation in section of part of two consecutive rotor discs showing the introduction of the cooling air into the insulating space at the low pressure end of the rotor; and the conduction of such air in series through consecutive stages of the rotor.

Fig. 6 diagrammatically shows a gas turbine plant embodying the invention.

Referring first to Fig. 6, a multistage gas turbine set incorporating the invention comprises for example a conventional air compressor A delivering compressed air through a conventional combustion chamber B to the multistage gas turbine C. Part of the compressed air is tapped off, preferably of the compressor A and passed through a cooler D to the gas turbine C where it is used as a gaseous cooling medium in a manner that will be described later with reference to Figs. 1 to 5. The compressor A is accordingly a means for circulating a gaseous cooling medium, or a source of unburnt air, and if the tapping-off of this air is effected from the highest compression stage as diagrammatically indicated in Fig. 6, this air is at the maximum pressure used in the gas turbine cycle.

Referring now to Figs. 1 and 2, the cooling medium is allowed to pass from the cavities between adjacent discs 1, 1' and 1'', 1''' respectively axially through a set of channels 3 between the inner ends of the blade attachment stubs 2a and the bottom of the corresponding recesses 1a in the rim of the disc and back in the reverse direction through another set of axial channels 4 formed between the outer ends of the projections 1b of the rim and the underside of the blade root platforms 2b.

A drum-shaped body is composed of separate sections of intermediate pieces 7 which are retained on the discs by means of circular flanges 5, 5a and recesses 6 in the rims of the discs engaging corresponding projections 17 of the intermediate pieces 7. The intermediate pieces 7 contain a cavity 8 which may be open on both ends and which is in communication through a port or ports 9 with the space between two adjacent discs such as 1 and 1'. Cavities 11 and 13 are left between the side walls of the piece 7 and the adjacent discs 1 and 1' respectively, cavity 11 connecting the channels 3 and 4 in disc 1. The cavity 13 is in communication with cavity 8 through a port or ports 12 so as to admit cooling medium into the channels 3 of disc 1', while being shrouded from channels 4 by a lip 14. A gap 16 is left between the rounded leading edge 2c of the platform of blade 2' and the lip 15 of the intermediate piece 7 allowing the cooling medium to emerge into the blade space and to form a comparatively cool boundary layer covering the platforms of the blade roots before mixing with the hot combustion gases.

On an arc of the circumference of the rotor disc corresponding to one such section the outer flange 5a is cut away as shown on the left hand side of disc 1' and right hand side of disc 1''' so as to allow the sections 7 of intermediate pieces

to be inserted radially from outside and then to be shifted circumferentially until all of the circumference but a gap corresponding to the arc of one section is filled. This gap is eventually closed by a special section consisting of two halves 1a, 1b, the sum of the axial dimensions of which is shorter than the distance between the two adjacent discs 1', 1''' so that they can be inserted radially and then moved axially towards the respective discs so as to engage the inner radial flanges 5 thereof. The ends of the half segments 1a, 1b, are blanked-off so that closed compartments 8b and 11a respectively are formed inside them, the function of which corresponds to that of the annular cavities 8 and 11, respectively formed in or by the ordinary segments 7; the compartment 11a connects the channels 3 and 4 of disc 1', whereas the compartment 8b is in connection with the cavity between the discs 1', 1''' through the port 9b and lines up with the channel 3 in disc 1''' a gap 16a between the rounded leading edge 2c of the blade root platform of blade 2''' and the lip 15a of segment 1b allows the cooling medium from channel 4 of disc 1' to emerge into the bladed space of the respective stage and to form there a comparatively cool boundary layer covering the platforms of the blade roots before mixing with the combustion gases.

A wedge-shaped piece 18 having a lightening hole 18a if desired is then driven home between these two halves 1a and 1b so as to secure them in position and this wedge-shaped piece 18 may then be permanently connected with the two halves by a welded seam 18b.

Such an arrangement is suitable for a series flow of air in zigzag, i.e. in the direction of the flow of the combustion gases in the inner channels 3 formed between the ends of the blade attachment stubs 2a and the bottom of the recesses 1a in the disc, and a reverse flow in the outer channels 4 formed between the tops of the projections 1b of the disc and the recesses formed between the blade root platforms 2b and the necks of the stubs 2a.

According to the embodiment shown in Figs. 3 to 3f adjacent discs 21, 21' are provided with flanges 20a, 20b overlapping one another with a spigoted joint leaving a trapezium-shaped groove 20 on the circumference which is filled with a seam of weld so as to combine the discs 21, 21' to a single built-up drum structure.

A circumferential groove 39a is made non-symmetrically through all the projections 21b of the rotor discs leaving a long serrated section on one side and a comparatively short one on the other side of the groove.

A corresponding recess 39b may be left in the serrated stubs 22a of the blade roots so that these two grooves form together a circumferential channel 39 when the serrated blades are assembled in their working position. Axial channels 23, 24 are again left between the inner end of the serrated blade stubs 22a and the bottom of the grooves 21a in the disc and between the tops of the projections 21b of the disc and the platforms 22b of the blades respectively. Circumferential flanges 25, 25a are arranged on one side of each disc rim, and separate intermediate pieces 27 are inserted between two adjacent discs 21, 21' in such a manner that they engage the recess 26 between the concentric flanges 25, 25a by means of an axial projection 33 of a radial wall portion 32 integral with a circumferential bridge portion 31 extending between two adjacent rows of blades 22, 22'. The intermediate pieces define an an-

nular space between themselves and the flanges 20a and 20b of the adjacent discs 21, 21'. The end of that bridge portion 37 on the side of the radial wall 32 forms a lip 30 that leaves a comparatively narrow gap 36 between its end and the leading edge of the platform 22b of the adjacent blade 22'. The other end of the bridge plate 37 has a radially inward pointing extension 35 serrated with the same fir tree profile as the blade attachment stubs 22a and of an axial dimension slightly smaller than the aforesaid circumferential groove 39b in the rotor disc. A rib 34 joins the platform 37, the serrated extension 35 and the wall portion 32. Adjacent platform sections 27 may be joined either by means of a spigotted joint 27d (Fig. 3d) or by means of an inserted metal strip 27e (Fig. 3e) forming a seal between the annular space 28 and the stream of combustion gases passing the blades 22, 22', which will remain substantially airtight and will at the same time permit expansion of the said platform sections.

Before the assembly of the blades with the rotor the aforesaid separate intermediate pieces 27 are dropped with their serrated radial extensions 35 into the said circumferential groove 39a of the disc and then shifted in an axial direction until the projection 33 of the radial wall portion 32 on the other side of the bridge piece 37 engages the recess 26 between the flanges 25, 25a of the adjacent disc 21'. The blades can then be inserted laterally in the usual way, and secure the bridge pieces 27 in their position.

Vent holes 29 are left in the circumference of the inner drum formed by the flanges 20a, 20b so proportioned as to allow the passage of the desired quantity of the cooling medium from the cavities formed between the two adjacent discs 21, 21' inside said inner drum into said annular cavity 28. From there the cooling medium flows through the channels 23, 24 in parallel streams in a direction opposite to the flow of the combustion gases. These streams mix in another annular cavity 31 formed between the rim of each disc and a ring-shaped wall formed by the wall portions 32 of all of the separate intermediate pieces 27. The cooling medium emerges from this second annular cavity 31 through a circumferential gap 36 between the aforesaid lip portions 30 of the intermediate pieces 27 and the leading edges of the blade platforms 22b so as to form a comparatively cool boundary layer covering the blade platforms before mixing with the hot combustion gases.

Referring now to Figs. 4 to 4c showing circumferential fixtures, the intermediate pieces 41, bridging the space between two adjacent discs 41, 41' respectively, are preferably oblique, i. e. approximately of parallelogram shape in plan view. These pieces 41 are again secured by the engagement of circumferential recesses with circumferential flanges 45, 45a, 45b respectively on opposite faces of adjacent discs. The last section 41a (Fig. 4, right hand side) to be inserted is again of an axial dimension which is shorter than the distance between adjacent discs 41, 41' so that it can be inserted radially and shifted axially to engagement with the one 41' of the adjacent discs, the remaining gap being closed by the radial insertion of a recessed piece 59 which can also be dropped in radially and shifted axially until it engages the other adjacent disc 41'', the remaining gap between these two portions being filled by a wedge-shaped member 51, the two portions 46a, 50 and the said wedge-

shaped member 51 being eventually welded together at 52.

The path of air (Figs. 4a and 4b) in this embodiment is preferably radially outward in the cavity between two adjacent discs 41, 41' and 41', 41'' respectively, then at 46 in an axial direction between two adjacent intermediate pieces 47 into a circumferential space 44a left between the platform 42b of the blades and the outer circumference of the rim of the disc. The air flows then radially inward through a recess left in the radial faces of adjacent blade attachment stubs 42a until it reaches another circumferential channel left at 43 between the inner end of the blade attachment stubs 42a and the bottom of the circumferential groove 41a left in the rim of the disc. From there the cooling air moves again radially outward in a recess left between the next pair of adjacent blade attachment stubs 42a into a circumferential channel 44b left between the outer circumference of the rim of the disc and the platform 42b of the blades, and from there in a substantially radial direction through a hole 42c arranged in the leading edge side of the blade root platform 42b so that the emerging air again forms a boundary layer of comparatively low temperature along the platforms of the rotor blades before mixing with the combustion gases.

Referring now to Fig. 5 the adjacent rotor discs 51 and 51' are again provided with spigotted flanges 50a, 50b, respectively, which after assembly are welded with one another by the seam 59. The space thus enclosed between the extreme low pressure stage disc 51' and the adjacent disc 51 is connected with the source of cooling medium, preferably unburnt air of a pressure at least equal to the highest pressure occurring in the gas turbine cycle. A flange 71 is provided on the downstream side of disc 51' and is equipped with an inward axial ledge 72. Pieces 70 similar in shape to the intermediate platform pieces 27 of Figs. 3 and 3b but generally shorter in the axial dimension are adapted to be inserted radially with their serrated inward extension 75 into the circumferential recess 59a of the disc 51' and shifted axially into the position shown in Fig. 5 in which they engage with their extensions 73 the ledge 72 of the flange 71. In this position they are held by the axial insertion from the left of the blades 52' having correspondingly serrated roots. The pieces 70 enclose between themselves and the disc 51' an air space 69 communicating with the space between the discs 51 and 51' by ducts 68.

Channels 53 and 54 are formed under the inner ends and under the platforms 52b of the blades, corresponding to the channels 23, 24, respectively, of the embodiment of Fig. 3. The leading edges 52d of blades 52' have a spigotted joint with the flange 69 of the intermediate platform pieces 57 which correspond otherwise substantially to the intermediate platform pieces 27 of Figs. 3 and 3b, in that they engage with their extensions 63 the grooves 56 between the circumferential projections 55, 55a of the discs 51, 51' etc. The radial wall portions 62 of the intermediate platform pieces 57 have wide openings 62a.

As will be seen from Fig. 5, this arrangement provides a series flow of the cooling medium from space 69 at the downstream side of the lowest stage through the channels 53, 54 holes 62a under the platforms 57 of the intermediate pieces 57 through the channels 53, 54 of the next higher stage, and so on, until the cooling medium is

eventually discharged at the upstream side of the rotor blades of the highest pressure stage in a way similar to that shown in Fig. 3 between the lips 30 and 36, the end pieces used for closing the channels 53, 54 of the highest pressure stage however corresponding otherwise to the end pieces 10 at the low pressure end.

In all the various embodiments referred to hereabove, severe temperature gradients in the rotor can be avoided by applying cooling medium at the blade roots.

Thus the rotor is kept cool enough to minimise creep in the blade attachment stubs, even when using comparatively low grade material for the rotor. Creep in the blade roots themselves is also kept to a minimum. By controlling the pressure of the cooling medium, any inward flow of the hot gases is prevented. As stated above, a boundary layer of cool air over the outside of the blades and of the intermediate platforms is set up by the escaping cooling medium.

The rim of the rotor discs of any of the embodiments may be divided into segments by radial slots (not shown) in a way known in itself, in order to allow an independent thermal expansion of that portion without setting up unduly high compressive stresses.

By the aforesaid improvements quick starting and changes of load and temperature of the gas turbine are permissible.

The construction described is applicable also to tapered rotors. Solid forged or built up rotors may be used and, as shown in the embodiments described, with reference to Figs. 3 and 5, the welding seams of built up rotors can be kept out of contact with the stream of combustion gases, a design which is applicable also to other embodiments.

The method of securing the intermediate pieces is unaffected by varying numbers of blades in adjacent blade rows.

What we claim as our invention and desire to secure by Letters Patent is:

1. In a multistage gas turbine a rotor comprising several rotor discs integral with one another and each comprising a main body, profiled projections of a cross sectional area restricted as compared with that of the said main body extending from its circumference, and an outer portion comprising a row of blades, each blade having an airfoil portion, a platform portion and a root section of a cross sectional area comparatively restricted adjacent the said platform portion and comparatively larger in a portion profiled complementary to and engaging with the said profiled projections of the main body, and separate platforms arranged between the platform portions of adjacent rows of blades at the same diameter as the said platform portions, complementary coolant conducting passageways formed in said profiled projections and said root sections, the said root sections, platform portions and separate platforms forming enclosed passages between them and the said main body, means connecting said passages and passageways for conducting a continuous stream of cooling air forming a heat insulating layer between the said main body and the said outer portion, the said root sections forming the only integral connection between the said airfoil portion and the said platform portion.

2. In a multistage gas turbine as set forth in claim 1 the said projection of the main body of the rotor being axially recessed and serrated, the said blades having correspondingly serrated roots

adapted to be axially inserted into the said recessed and serrated projection, a circumferential groove in the said projection and an opposite groove in each blade root, these grooves forming together a circumferential duct, the said intermediate platforms having equally serrated projections pointing inwards of an axial dimension shorter than the said groove in the rotor, radially inserted into the said groove and axially moved into engagement with the serrated recesses of the rotor and held thereby the serrated blade roots, the total axial length of the said serrated projections of the intermediate platforms plus the serrated blade roots being substantially equal to the axial length of the serrated recesses in the said projection of the main rotor body.

3. In a multistage gas turbine as set forth in claim 1 cylindrical flanges on the sides of the said discs, adjacent flanges being welded together, the said intermediate platforms separating the said welded flanges from the stream of hot working fluid passing through the said rotor blades.

4. In a multistage gas turbine a rotor as claimed in claim 1 wherein the said separate platforms are anchored in the said projections of the main body and form with the adjacent rotor discs substantially closed drums exposed inside to the cooling air flowing through the said passages.

5. In a multistage gas turbine as set forth in claim 4 at least one of the said intermediate platform pieces comprising two parts of a total axial dimension smaller than the distance between adjacent discs so as to be inserted radially and then shifted axially into engagement with the respective adjacent disc, and wedge members driven radially between the said parts of platform pieces and subsequently welded to the said parts.

6. In a multistage gas turbine as set forth in claim 4 means for circulating a gaseous cooling medium such as compressed air through the said passages and past the inside of the said intermediate platforms.

7. In a multistage gas turbine as set forth in claim 6, the said blades being inserted axially into the said projection of the main rotor body, and the said means for circulating the cooling medium directing the same firstly axially in the direction of the main working fluid stream through the said passages under the inner ends of the blade roots of a rotor stage, then deflecting the said cooling medium radially outwards, and directing the said cooling medium in a direction opposed to that of the main working fluid stream through the said passages under the blade platforms, and eventually discharging the cooling medium into the main working fluid stream at the upstream side of the blades of the said rotor stage.

8. In a multistage gas turbine as set forth in claim 6, the said blades being inserted axially into the said projection of the main rotor body, the said means for circulating the cooling medium directing the same in parallel axial streams in the direction opposite to that of the main working fluid stream both through the said passages under the inner blade root ends of a rotor stage and through the said passages under the blade platforms of the said rotor stage, and eventually discharging the cooling medium at the upstream side of the rotor blades of the said rotor stage.

9. In a multistage gas turbine as set forth in claim 6 cylindrical flanges on the said discs forming inner drums the outside radius of which is less than the radius defining the bottoms of the recesses in the said outer portions, at least one of the said flanges being perforated by holes adapted to admit metered quantities of cooling medium from the space within the said cylindrical flanges to the said insulating spaces arranged in separate groups of the outer rotor portion, each group comprising at least one row of the said blade roots, blade platforms and intermediate platforms and including the said passages for the cooling medium, the said cooling medium being discharged thereafter into the main working fluid stream passing the blades proper of the gas turbine.

10. In a multistage gas turbine as set forth in claim 9 means for connecting the said insulating spaces of consecutive rotor stages in series, the said means for supplying the cooling medium being connected to the insulating space of a low pressure stage, and the said cooling medium being discharged into the said main working fluid stream at the upstream side of the rotor blades of a higher pressure stage.

11. In a multistage gas turbine as set forth in claim 10 the said means for the supply of cooling medium being connected to the insulating space on the downstream side of the lowest pressure stage of the rotor, the said means passing the said cooling medium consecutively through the

insulating spaces and passages of all stages of the said rotor, and eventually discharging it into the said main working fluid stream at the upstream side of the rotor blades of the highest pressure stage.

12. In a multistage gas turbine as set forth in claim 10 a hollow central portion of the rotor in supply connection on the one hand with a source of cooling medium, and on the other hand with the said insulating space of at least one rotor stage.
